COMBINED CROWDING AND STAKING TOOL
FOR WATCHMAKERS

Jes I. Hansen, Denver, Colo.

Application May 4, 1936, Serial No. 77,806

6 Claims. (Cl. 29—88)

This invention relates to a special tool for watchmakers and relates more particularly to a tool for removing and replacing friction jewels and bushings in watch movements. It is the 5 modern practice in watchmaking to employ jewels mounted in a sleeve or bushing designed to be pressed into a receiving opening in the watch plate with sufficient pressure to frictionally maintain themselves in place without the use of 10 screws.

The usual watchmaker's staking tool is designed to be struck with a hammer and when used on friction jewels, is not satisfactory. The disadvantage of the usual staking tool is that it is impossible to judge the strength of the hammer 15 blow, and it is therefore difficult to drive a friction jewel bushing to exactly the proper position. If it is driven too far, the plate must be reversed and the jewel driven back. After several attempts, it might be finally perfectly located.

The principal object of the present invention is to provide a staking tool which can be used for the usual purposes of such a tool and also used for micrometric crowding or pushing, so 25 that a friction jewel bushing may be removed or accurately pushed into place without the use of a hammer and without scratching or damaging the bushing.

Another object of the invention is to so construct the device that should it be desired to use 30 the tool with a hammer for the usual staking operations it may be so used without interfering with the accurate crowding or pushing feature thereof.

A further object is to so construct the tool 35 that it can make use of the usual watchmaker's staking tool, punches and stumps, thereby making the purchase of additional punches unnecessary.

Other objects and advantages reside in the 40 detail construction of the invention, which is designed for simplicity, economy, and efficiency. These will become more apparent from the following description.

In the following detailed description of the 45 invention reference is had to the accompanying drawing which forms a part hereof. Like numerals refer to like parts in all views of the drawing and throughout the description.

In the drawing:

Fig. 1 is a perspective view illustrating the invention ready for use as an ordinary staking tool.

Fig. 2 is a vertical section therethrough, taken 50 on the line 2—2. In this view the tool is set up 55 for a crowding or pushing operation.

Fig. 3 is a detail horizontal section, taken on the line 3—3, Fig. 2.

Fig. 4 is a detail view of the cap member employed for converting the tool from a staking tool to a crowding tool.

Fig. 5 is a detail view of a typical watchmaker's stump of the type which may be employed with the invention.

The improved staking and crowding tool employs a base 10 above which a curved, punch-holding standard 11 projects. The top of the base 10 is formed with a flat work table 12 drilled as shown at 15 to receive the usual watchmaker's stump 13. These stumps of course are furnished in various sizes with various bores. The standard 11 terminates immediately over the stump 12 in a horizontally slotted vertically drilled extremity 14. The vertically drilled hole is positioned accurately over the stump socket 15.

A threaded punch tube 16 passes vertically 20 through the extremity 14 and is supported therein in an adjusting nut 17. The nut 17 is accurately held in place by the horizontal slot and it is accurately threaded to receive the threaded tube 16. The tube 16 is prevented from rotating 25 by means of a set screw or pin 23 which enters a vertical keyway 18 in the threaded tube. The lower extremity of the sleeve 16 is tapered and slotted to form a spring chuck 19. The internal diameter of the sleeve 16 is such as to slidably 30 receive one of the usual watchmaker's punches, such as indicated at 20. The resiliency of the chuck 19 is such as to cause it to frictionally engage the punch 20 to hold it in any desired suspended position therein.

As thus far described, the device may be used as the usual staking tool. That is, the work may be placed upon the stump 13 and the punch 20, the upper extremity of which projects above the tube 16, may be struck with a hammer to do any desired staking work.

To convert the tool into a crowding tool, a cap 21 is provided. The cap is internally threaded so that it may be screwed upon the upper extremity of the sleeve 16 so that its interior will engage the upper extremity of the punch 20.

With the cap in place, it can be readily seen that if the nut 17 is rotated, it will cause the cap to push or crowd the punch downwardly toward 50 the stump 13, with any desired degree of pressure. Reversal of the nut 17 causes the spring chuck 19 to raise the punch. It is preferred to mark the top of the nut 17 with a micrometer index 22 so that the operator may move the punch 20 55

downwardly any predetermined degree of distance.

It can be readily seen that, with a watch plate resting on the stump 13 and a friction jewel positioned over the jewel opening in the plate, the operator can by rotation of the nut 22 gently crowd the jewel into its opening. If he knows in advance the length of the jewel bushing, he can by watching the graduations 22, know when he 10 has forced the jewel to an exactly flush position. The punches 20 and the stumps 13 are of course interchangeable as in the usual staking tool.

Arbor press clamps etc. have been designed so that by rotating a screw, pressure may be exerted. 15 Such a press is unsatisfactory for the present purpose since the lower extremity of their punch must rotate and in rotating it will scratch or mar the jewel bushing. It is desired to call attention to the fact that in the present invention there is 20 no frictional movement between the punch and jewel bushing so that the latter is not marred or damaged in any way.

It is desired to call particular attention to the micrometer scale 22. This scale is positioned on 25 the top of the knurled nut 17 so that it is not interfered with by the fingers of the operator, and is readily visible when in use. An indicating point 24 is provided for reading the index 22.

While a specific form of the improvement has 30 been described and illustrated herein, it is desired to be understood that the same may be varied, within the scope of the appended claims, without departing from the spirit of the invention.

35 Having thus described the invention, what is claimed and desired secured by Letters Patent is:—

1. A watchmaker's tool comprising: a supporting frame; a work table in said frame; an arm 40 extending over said work table; a bifurcated extremity on said arm; a nut positioned in said bifurcated extremity; a vertical threaded tube passing through said extremity and through said nut and threaded into the latter; a punch slid- 45 ably mounted in said threaded tube; means for preventing upward movement of said punch in said tube; an index scale on the upper face of said nut; a point cooperating with said scale to indicate the amount of rotation of said nut; and 50 means for preventing said tube from rotating in said extremity.

2. A watchmaker's tool comprising: a supporting frame; a work table in said frame; an arm 55 extending over said work table; a bifurcated extremity on said arm; a nut positioned in said bifurcated extremity; a vertical threaded tube passing through said extremity and through said nut and threaded into the latter; a punch slid-

ably mounted in said threaded tube; means for preventing upward movement of said punch in said sleeve; an index scale on the upper face of said nut; a point cooperating with said scale to indicate the amount of rotation of said nut; 5 means for preventing said tube from rotating in said extremity; and friction means on said tube for engaging said punch to hold the latter in position.

3. A combined staking tool and press for 10 watchmakers comprising: a base; means for supporting a stump in said base; a standard extending over said stump; a vertical, threaded tube in said standard over said stump; a punch extending through said tube; an adjusting nut threaded 15 on said tube so that rotation thereof will move said tube vertically; a resilient clutch on the lower extremity of said tube for preventing downward movement of said punch; and means for preventing said punch from moving upward 20 in said sleeve.

4. A combined staking tool and press for 25 watchmakers comprising: a base; means for supporting a stump in said base; a standard extending over said stump; a vertical, threaded tube in said standard over said stump for receiving a punch; an adjusting nut threaded on said tube so that rotation thereof will move the latter vertically; and a cap member threaded onto said tube and closing the upper extremity thereof so 30 that downward movement of said tube will cause said cap to contact said punch to force the latter downward.

5. A watchmaker's tool comprising: a supporting 35 frame; a work table in said frame; an arm extending over said work table; a bifurcated extremity on said arm; a nut positioned in said bifurcated extremity; a vertical threaded tube 40 passing through said extremity and through said nut and threaded into the latter; a punch slidably mounted in said threaded tube; means for preventing upward movement of said punch in said tube; and means for preventing said tube from rotating in said extremity.

6. A watchmaker's tool comprising: a supporting 45 frame; a work table in said frame; an arm extending over said work table; a bifurcated extremity on said arm; a nut positioned in said bifurcated extremity; a vertical threaded tube 50 passing through said extremity and through said nut and threaded into the latter; a punch slidably mounted in said threaded tube; means for preventing upward movement of said punch in said tube; means for preventing said tube from 55 rotating in said extremity; and friction means on said tube for engaging said punch to hold the latter in position.
